REEL

Paul S. McCann, La Grange, Ill., assignor to
Western Electric Company, Incorporated, New
York, N. Y., a corporation of New York

Application January 11, 1936, Serial No. 58,636

7 Claims. (Cl. 206—59)

This invention relates to reels and more particularly to metallic reels for holding cable or other heavy material susceptible of being wound thereon.

5 An object of this invention is the provision of an improved reel lag which is of the required structural strength, economical to manufacture and durable in service.

In accordance with the above object the invention contemplates in one embodiment thereof channel shaped metal lags for use in a metal reel which includes annular channel shaped rims surrounding the peripheries of the heads for removably securing the lags for enclosing the reel, the 10 side arms of the channel shaped lags being flared outwardly and notched for substantially one-half the depth of the lag at their end portions which extend into and are supported within the channel shaped rims. The narrowing of the end portions 15 of the side arms of the channel lags appreciably strengthens the lags so that they successively withstand impact stresses encountered in normal service. Also this lag construction permits a reduction in the distance between the side arms 20 of the channel rims which results in a strengthening 25 of the rims.

Other objects and advantages of this invention will more fully appear from the following detailed description taken in conjunction with the accompanying drawing, wherein

30 Fig. 1 is a front elevational view, partly in section, of a reel embodying the features of the invention;

Fig. 2 is a fragmentary side view, partly in section, of the reel shown in Fig. 1;

35 Fig. 3 is a perspective view of one of the lags for enclosing the reel;

Fig. 4 is a perspective view of a modified form 40 of lag, and

Figs. 5, 6, and 7 are fragmentary sectional views 45 of modified forms of the reel head construction of Fig. 1 showing the improved lag in cooperating relation therewith.

Referring now to the drawing there is disclosed a metal reel having heads designated generally as 10. Extending from a central circular portion (not shown) of each head 10 are inner channel shaped spokes 15, one of which is illustrated fragmentarily in Fig. 2, the spokes being suitably shaped at their inner ends to abut the periphery of the central portion and are welded thereto. Arc welded to the outer ends of the spokes 15, as indicated at 16, is an annular channel shaped portion 17, the spokes extending between the side arms thereof. A metal drum 25 50 is secured between the heads 10 for sustaining a cable 26, or other heavy material that may be wound thereon. Secured to and extending outwardly from the outer periphery of the drum 25 are a plurality of segmental channel shaped head

5 plates 35 which serve as enclosing end walls for the cable 26 wound on the drum, the adjacent ends of the plates being slightly spaced as indicated at 36. The ends of the side arms of the channel head plates 35 are in alinement and the inner arms thereof engaging the periphery of the drum 25 are alined with the annular ends of the drum, the latter ends being arranged inside the outer side arms of the annular channel shaped portion 17.

10 Extending across the spaces 36 between the head plates 35 are outer channel shaped spokes 37, the side arms of the spokes 37 being notched at their inner ends so that their edge faces abut the annular channel shaped portion 17 and also 15 the inner side arms of the head plates 35. The spokes 37 are secured to the head plates 35 by spot welding, as indicated at 38 (Fig. 2), and the head plates 35 are secured to the drum 25 and the drum to the annular channel shaped portions 17 20 by spot welding, as indicated at 39 (Fig. 1), the spokes being further secured to the portions 17 by arc welding, as indicated at 40.

An annularly formed channel shaped rim 42 surrounds the periphery of each head 10 of the 25 reel. The rim 42 is secured to the head 10 by being spot welded to the outer side arms of the head plates 35, as indicated at 43 (Fig. 1). For enclosing the reel between the rims 42 of the heads 10 there are provided metal lags 44 which 30 serve to protect the cable 26 wound on the drum 25. In one embodiment of the invention (Figs. 1, 2, and 3) the lags 44 are channel shaped with their opposite longitudinally spaced end portions fitting within the opposed inside channels of the 35 head rims 42. As clearly shown in Figs. 2 and 3 side arms 45 or flanges of the channel lag 44 are flared outwardly with their longitudinal edges formed to provide outwardly extending open beads, the outward flaring of the arms permitting 40 a compact nesting of the lags when removed from the reel and the reel is being returned to the cable supplier. The opposite longitudinally spaced ends of the side arms 45 are notched, as indicated at 46, for substantially one-half their 45 width, the notches extending inwardly from the opposite ends of the side arms 45 a distance substantially equal to the inside width of the side arms of the annular head rims 42. The notching of the opposite ends of the channel lags 44 50 it will be obvious results in a narrowing of the side arms 45 thereof and consequently greater resistance to deformation when the reel is in normal service wherein it is roughly handled and subjected to impact stresses.

55 The lags 44 are entered within the opposed channels of the head rims 42, after the cable 26 has been wound on the reel, through suitable slots (not shown) formed in the outer arms of the head rims. The dimensions of the notched 60

ends of the lags 44 and the length of the lag as a whole are such that the lags may freely slide along the opposed channels of the head rims 42. After a sufficient number of lags 44 have been entered through these slots and moved about the periphery of the reel to form a complete enclosure, locking members (not shown) are closed over the slots to secure the lags in position. A more complete disclosure of the means for locking the lags 44 in position is not believed necessary to a full understanding of the present invention. For a detailed illustration and description of a lag locking means which may be employed reference may be had to U. S. Patent 1,944,188 to L. R. McGuire, dated January 23, 1934, which also illustrates a channel rim slotted to permit insertion of the lags.

In Fig. 4 there is shown a modified form of the channel shaped lag 44 hereinbefore described which in addition to being notched at opposite ends of its side arms 45 has the lower ends of the side arms curved, as indicated at 48, throughout the length of the lag, the width of the side arms at a point intermediate the notched ends being similar to that of Fig. 3 but appreciably less at the notched ends. For simplicity in forming the lag of Fig. 4 the curved ends of the side arms 45 thereof are formed with outwardly extending closed beads instead of open beads as in Fig. 3 wherein the lower ends of the side arms 45 are straight between the notched ends. The truss like formation of the lag of Fig. 4 it will be apparent has all the advantages of the lag 3 with the additional advantage of a saving in weight.

Figs. 5, 6, and 7 show slightly modified forms of the reel construction of Fig. 1 at a point adjacent the periphery of the reel head. In Fig. 5 the outer side arm of the segmental channel shaped head plate 35 abuts the inner surface of the inner side arm of the annular channel shaped rim 42 instead of the outer surface of said arm of the rim as shown in Fig. 1. The outer side arm of the head plate 35 of Fig. 6 in addition to abutting the inner surface of the inner side arm of the rim 42 is extended outwardly and at right angles and abuts the inner surface of the rim portion which interconnects the side arms thereof. In Fig. 7 the head plate 35 which is L-shaped in cross-section at its inner end terminates in line with the inner surface of the inner side arm of the channel rim 42. The head plates as shown in Fig. 7 may also be formed with an inwardly extending embossment 50 concentric with the periphery of the reel head and immediately inside the lags 44, which embossment has a shock absorbing effect when the reel is subjected to deleterious impact stresses when in normal service.

A metal reel constructed as above described with the parts secured together by welding results in a rigid and durable reel for handling cable wound thereon and by enclosing the reel with channel shaped metal lags 44 having opposite ends of the side arms 45 thereof which are entered in the opposed channels of the head rims 42 notched for substantially one-half their width an appreciably stronger lag construction is provided. The narrowing of the side arms of the channel lags appreciably strengthens the lags against impact stresses encountered in normal service of the reel. Furthermore by reducing the width of the side arms 45 of the channel lags 44 the distance between the side arms of the channel shaped rims 42, in which the notched ends

of the lags are entered, may also be reduced, thus providing a stronger rim construction.

It is, of course, to be understood that the invention is not limited to the specific embodiments described, but is to be restricted only by the scope of the appended claims.

What is claimed is:

1. A cable reel comprising spaced metallic heads, a drum connected therebetween, and channel shaped lags for enclosing the reel, each head having an annular peripheral member adapted to support opposite ends of said lags, said channel lags having their side arms narrowed at their ends where they rest on said members for increasing their resistance against deformation by impact stresses.

2. A cable reel comprising spaced metallic heads, a drum connected therebetween, and channel shaped lags for enclosing the reel, each head having a peripheral annular channel shaped lag supporting member, said channel lags having their side arms notched to reduce the width thereof at their end portions which extend into the supporting members for strengthening the lags against deformation by impact stresses.

3. In a metal reel, a plurality of metallic heads, each including an annular channel member surrounding the head, and a plurality of metallic channel lags extending between and engaged at opposite ends in the opposed channels of said members for enclosing the reel, the side arms of said channel lags being substantially decreased in width at their end portions engaged in said members as compared to the width thereof intermediate said members for increasing their resistance against deformation by impact stresses.

4. In a metal reel, a plurality of metallic heads, each including an annular channel member surrounding the head, and a plurality of metallic channel lags extending between and engaged at opposite ends in the opposed channels of said members for enclosing the reel, the side arms of said channel lags being notched to decrease the depth of the channel at the ends of the lags engaged in said members for increasing their resistance against deformation by impact stresses.

5. A lag for cable reels having spaced heads comprising a channel shaped member having a base forming an outer surface and arms extending toward the interior of the reel and adapted at opposite longitudinally spaced end portions to engage reel heads, said arms being substantially reduced in width at said end portions to increase their lateral strength at the points of engagement with the reel heads.

6. A lag for cable reels having spaced heads comprising a channel shaped member having a base forming an outer surface and arms extending toward the interior of the reel and adapted at opposite longitudinally spaced end portions to engage the reel heads, said arms being notched at said end portions to increase their lateral strength at the points of engagement with the reel heads.

7. A lag for cable reels having spaced heads comprising a channel shaped member having a base forming an outer surface and arms extending toward the interior of the reel and adapted at opposite longitudinally spaced end portions to engage the reel heads, said arms having their greatest width substantially at their midpoints and tapering toward said end portions at the points of engagement with the reel heads.

PAUL S. McCANN.
